UNITED STATES PATENT OFFICE.

ROBERT L. WILLIAMSON, OF ERWIN, TENNESSEE.

TUMBLER PADLOCK.

Application filed March 1, 1922. Serial No. 540,229.

To all whom it may concern:

Be it known that I, ROBERT L. WILLIAMSON, a citizen of the United States, residing at Erwin, in the county of Unicoi and State 5 of Tennessee, have invented certain new and useful Improvements in Tumbler Padlocks, of which the following is a specification, reference being had to the accompanying drawings.

10 This invention relates to locks, and particularly to the locking mechanism of padlocks.

The general object of this invention is to provide a padlock wherein the shackle is 15 held from removal by a bolt engaging both arms of the legs of the shackle, and to provide a barrel whereby the bolt may be shifted out of its locking position, and provide a series of tumblers so designed that 20 normally they impede or prevent the movement of the barrel but which, upon the insertion of the proper key, will all be shifted to a correct position to permit the oscillation of the barrel and the consequent disengagement of the bolt from the shackle.

25 A further object is to provide a construction of this kind wherein the barrel is formed with a longitudinally extending stump, the tumblers each being formed with 30 a longitudinally extending slot into which the stump is adapted to pass, the tumblers being adapted to be shifted with their slots in register to permit the passage of the stump when the proper key is inserted 35 within the padlock.

Other objects will appear in the course of the following description.

My invention is illustrated in the accompanying drawings, wherein.—

40 Figure 1 is a side elevation of a padlock constructed in accordance with my invention;

Figure 2 is a vertical sectional view therethrough;

45 Figure 3 is a section on the line 3—3 of Figure 2;

Figure 4 is a section on the same line as Figure 3, but showing the locking bolt out of its locking position;

50 Figure 5 is a section on the line 5—5 of Figure 2;

Figure 6 is a like view to Figure 5, but showing the tumblers in their unlocking position;

55 Figure 7 is an end view of the padlock; Figure 8 is a side elevation of the key;

Figure 9 is a perspective view of the barrel;

Figure 10 is a perspective view of the locking bolt;

Figure 11 is a perspective view of the shackle;

Figure 12 is a perspective view of one of the tumblers and spring therefor.

Referring to these drawings, 10 designates the casing of the padlock, which is elliptical in cross section and provided with the ends 11 and 12. One of these ends is provided with perforations 13 and 14 to receive the legs of the shackle 15. These 15 legs are unequal in length and the short leg 16 is formed with a notch 17 wherein the locking bolt engages, the other leg being formed with a notch 18 directly opposite the notch 17 and on the same level, and 20 midway between this notch 18 and the end of the leg the leg is provided with the inwardly extending lug 19 which, when the shackle is fully inserted, is adapted to bear against a stop or shoulder 20 formed in the 25 casing of the lock. The casing is, of course, to be formed in two or more sections or parts, these sections or parts being engaged with each other in any suitable manner so as to prevent their unauthorized detachment.

Rotatably mounted within the casing is the barrel 21. One end of this barrel is reduced, as at 22, and extends through an opening in one end of the casing and is provided with a slot 23 for the key 24, the key being illustrated in Figure 8. At its opposite end the barrel is formed with a reduced portion 25 constituting a trunnion for the barrel and supported in any suitable bearing in the adjacent end wall. Thus the barrel may be oscillated by the insertion of the key. Inward of the trunnion 25 the barrel is formed with an annular shoulder 26 upon which the central portion of the bolt 27 rides. This bolt 27 has a circular opening 28 at its middle into which the shoulder 26 fits, and this opening 28 has an arcuate extension 29, into which a lug 30 projecting from the shoulder 26 is adapted to engage.

It will be obvious now that the barrel may be given a certain rotation, as for instance approximately a quarter rotation, without affecting the bolt, but that when the lug 30 strikes the ends of the arcuate slot 29, the bolt will be oscillated with the barrel and will shift from a position where its

ends are in engagement with the notches 17 and 18, as illustrated in Figure 4, so as to permit the withdrawal of the shackle, and that a reverse movement of the barrel will 5 turn the bolt to the position shown in Figure 3 where it engages in these notches and prevents the removal of the shackle. A spring 31 bears at one end against the wall of the casing and at its other end is attached 10 to the bolt and acts to urge the bolt into its locking position.

The barrel is segmental in cross section, the transverse faces of the barrel being disposed at an obtuse angle to each other, as 15 illustrated in Figure 5, and forming an extension of the periphery of the barrel and extending longitudinally the entire length of the barrel is a peripherally curved flange or "stump", designated 32. It will be seen 20 that the key slot 23 opens upon the diametrical or transverse face of the barrel so that when the key is inserted in the barrel, the toothed edge of the key will project beyond these transverse faces and toward the edge 25 of the stump.

Pivoted between the abutments 33 and 34 are a plurality of tumblers 36, one of which tumblers is illustrated in Figure 12. These tumblers are adapted to bear upon the dia- 30 metrical face of the barrel when the barrel is in the position shown in Figure 5 and are urged against this face by springs 37. Each of the tumblers is formed with a slot 38 which extends inward from its free edge, 35 this slot being of such shape that it may receive the stump 32 when the tumbler is in proper position and will permit the barrel to rotate for a quarter turn or any other desired angle. I do not wish to be limited to 40 the particular shape of this slot. I have illustrated the slot 38, however, as being curved and having the same degree of curvature as the stump.

All of the tumblers are slotted, as at 38, 45 and when all of the tumblers are disposed with their slots in register with each other, then the stump 32 can pass into all of the slots at the same time and the barrel can be rotated. If, however, any one of the tum- 50 blers is depressed unduly or raised unduly, it will be obvious that that particular tumbler will bar the passage of the stump and will prevent the lock from being released. The key is so formed that when it is inserted 55 it will raise the depressed tumblers, that is tumblers which are depressed to such a degree that their slots are not in alignment with the path of movement of the stump to an extent sufficient to bring the slots of these 60 depressed tumblers into line with the slots of the other tumblers and permit the entrance of the stump. To this end, the key is made with raised teeth separated from each other by depressions, and the tumblers are so 65 formed along their lower edges in an ob-

vious manner as to be all raised to the same extent when the key is rotated. When the key is inserted it is in the position shown in Figure 5 and the barrel may oscillate to a slight degree or until the edge of the stump 70 comes against the tumblers. Just before the edge of the stump comes to the tumblers, however, the raised teeth of the key engage those tumblers which are depressed and lift these tumblers up to bring them into line 75 with the stump, and then a further movement of the barrel carries the stump into the slot 38 and a quarter turn of the barrel is effected, which serves to shift the bolt from its locking position. Of course, even 80 though the key be now withdrawn, the tumblers cannot fall back to their original position and it requires that the key shall be reversely turned to reversely turn the barrel and as soon as the stump has cleared the 85 ends of the tumblers and the key has cleared the ends of the tumblers, the tumblers will again drop to their impeding position. Any number of tumblers may be used but normally about twelve tumblers will be suffi- 90 cient to form a very large number of combinations, and obviously more tumblers than twelve may be used if desired.

It will be seen that with this construction the shackle is held engaged at two points, 95 thus making it very difficult to insert an instrument through the shackle and pry it out from the lock casing. It will be seen that the bolt bears against the end of the lock casing so that there is no liability of the bolt being bent or deformed, and in order to detach the shackle from the lock casing it would be necessary to break the casing unless, of course, the proper key be used. No strain comes upon the tumblers and any 100 force exerted in turning the key is supported by practically all of the tumblers so that the tumblers cannot be broken.

While I have illustrated a construction which is particularly effective for this purpose, it is obvious that the principle of the invention might be embodied in other forms and I do not wish to be limited to the details illustrated, as these might be changed in many ways without departing from the 115 spirit of the invention as defined in the appended claims.

I claim:—

1. A padlock of the character described comprising a casing, a U-shaped shackle insertible into the casing and having a notch in one leg, a barrel axially oscillatable within the casing and having an axial key slot opening upon the end of the casing, a bolt mounted concentric to the barrel and adapted to be oscillated into or out of engagement with the notch by an oscillation of the barrel, the bolt and barrel having limited relative movement around their common axis, and a series of tumblers normally impeding the oscillation 130

of the barrel to an unlocking position but shiftable out of the unlocking position by the insertion of a key.

2. In a padlock, a lock casing, an axially oscillatable barrel mounted in the lock casing and having a longitudinally extending key slot opening upon one end of the casing, a bolt mounted upon the barrel and oscillatable therewith, the shackle having a notch with which the bolt is adapted to engage in one position of the barrel, and means for preventing an oscillation of the barrel comprising a plurality of tumblers normally disposed to impede said oscillation and adapted 10 to be shifted out of such impeding position by the insertion of the key into the shackle.

3. A padlock of the character described comprising a casing, a U-shaped shackle insertible into the casing and having a notch in one leg, a barrel axially oscillatable within the casing and having an axial key slot opening upon the end of the casing, a bolt mounted concentric to the barrel and adapted to be oscillated into or out of engagement with the notch by an oscillation of the barrel, the bolt having an arcuate slot, a barrel having a lug operating within said slot to thereby permit the barrel to have limited movement relative to the bolt, and a series of tumblers normally 25 impeding the oscillation of the barrel to an unlocking position but shiftable out of the unlocking position by the insertion of a key.

4. A padlock including a casing, a U-shaped shackle insertible into the casing and having notches in its legs, an axially rotatable barrel mounted in the casing, an oscillatable bolt carried upon the barrel and oscillatable therewith, the barrel carrying a longitudinally extending stump, the stump 30 being curved concentric to the axis of rotation of the barrel and the barrel being segmental in form and having a key slot opening upon the diametrical face of the barrel and through one end of the barrel, a plurality of tumblers normally disposed in a 40 position to impede the stump and the movement of the barrel, and key actuated means insertible into the barrel adapted to raise the tumblers to permit a movement of the stump 45 and barrel.

5. A lock including an axially rotatable barrel segmental in cross section and having a longitudinally extending key slot opening upon the diametrical face of the barrel and 55 upon one end thereof, the barrel carrying a stump extending longitudinally of the barrel and curved concentrically to the axis thereof, a plurality of tumblers disposed in a position to impede the movement of the 60 stump and of the barrel, key actuated means for shifting the tumblers to a position to

permit the movement of the stump and barrel, and a locking bolt operatively connected to be shifted by the barrel.

6. A lock comprising a casing, an axially 65 rotatable barrel mounted therein segmental in cross section and having a longitudinally extending key slot opening at one end of the barrel and upon the diametrical face of the barrel, a stump carried by the barrel extending longitudinally thereof and curved concentric to the axis thereof, a locking bolt operatively connected to be shifted by a rotation of the barrel, a plurality of tumblers disposed in the path of movement of the 70 stump, each of said tumblers having a longitudinally extending slot into which the stump is adapted to pass when the tumblers are shifted to a predetermined position, and a key insertible through the end of the 75 barrel and adapted to shift said tumblers to their unlocking position.

7. A padlock comprising a casing, one end of the casing being formed with a central bearing and the opposite end of the casing 80 with openings, a U-shaped shackle having a long and a short leg, the long leg being insertible through one of the openings and having a stop limiting the outward movement of the shackle, both of said lugs having facing 85 notches, a barrel oscillatably mounted between the ends of the casing, the barrel having a trunnion extending through said opening in the end of the casing, the barrel being segmental in cross section and having a 90 longitudinally extending key slot opening upon the diametrically opposite face of the barrel and through the trunnion thereof, the opposite end of the barrel being formed with a circular shoulder having an outwardly 95 projecting lug, a locking member enclosing said shoulder and having an arcuate slot into which the lug projects, said locking member being adapted to engage in the notches of the shackle, a stump extending longitudinally of the barrel and curved concentrically 100 thereto over the diametrical face of the barrel, a plurality of tumblers pivotally mounted within the casing and having slots for the reception of the stump, springs urging said 105 tumblers into a position where certain of the tumblers are disposed in the path of movement of the stump, and a key insertible through the slot in the barrel and formed upon one edge to shift the tumblers in such 110 position that the slots of all the tumblers are in alignment with the stump to thereby permit the rotation of the barrel and the movement of the bolt.

In testimony whereof I hereunto affix my 115 signature.

ROBERT L. WILLIAMSON,
